UNITED STATES PATENT OFFICE.

CARL JOHNSON, OF CHEAKAMUS, BRITISH COLUMBIA, CANADA.

AEROPLANE.

1,144,847.

Specification of Letters Patent. Patented June 29, 1915.

Application filed September 16, 1914. Serial No. 861,983.

To all whom it may concern:

Be it known that I, CARL JOHNSON, a subject of the King of Sweden, and a resident of the city of Cheakamus, British Columbia, of the Dominion of Canada, have invented certain new and useful Improvements in Aeroplanes, of which the following is a specification.

My invention relates to improvements in aeroplanes, and has for its object the production of an aeroplane which will be so designed as to be adapted to prevent disaster through falling.

A further object is the production of an aeroplane as mentioned, which will be of durable and economical construction, and efficient in use.

Other objects will appear hereinafter.

The invention consists in the combinations and arrangements of parts hereinafter described and claimed.

The invention will be best understood by reference to the accompanying drawings forming a part of this specification, and in which,

Figure 1 is a top plan view of an aeroplane in flying condition, embodying my invention, the central portion or flexible fabric of the plane of the machine being omitted, Fig. 2 is a side elevation of Fig. 1, Fig. 3 is a view similar to Fig. 2 showing the machine in parachute form, the upper end portion of the rudder-carrying arm being broken off, and Fig. 4 is a front elevation of Fig. 3 showing the central portion or flexible fabric of the plane arranged in position.

The preferred form of construction, as illustrated in the drawing, comprises a plane substantially rectangular in form consisting of a peripheral frame A and a central portion B formed of a suitable flexible material such as fabric, the periphery of said central portion B being secured to said frame. Said frame is of variable or adjustable size and to this end is formed of a plurality of telescoping sections 1 and 2, the members 1 being in the form of rods, the ends of which slidably engage with the sections 2 which are in the form of tubes. With the arrangement set forth, it will be seen, that when the frame A is distended or enlarged in dimensions, the central portion B of the plane will be drawn taut so as to be substantially coplanar with said frame and result in the formation of a substan-

tially flat plane such as is necessary in flying. Upon diminishing of the size of said frame, it will be seen, that the peripheral portion of the central portion B of the plane will be crimped or drawn together so as to permit of said portion B flexing upwardly into parachute form as shown in Fig. 4. This enlarging or diminishing of the size of frame A is effected by means of two sets of rods arranged for operation above and below said frame. The lower set of rods comprises rods 3 pivotally connected at their outer ends with the front and rear portions of said frame medially of the ends thereof. Pivotally connected with the corners of said frame are inwardly extending rods 4. The upper set of said rods comprises rods 5 corresponding with and connected to frame A in substantially the same manner as the rods 3, and rods 6 corresponding with and connected to frame A in substantially the same manner as the rods 4. The inner ends of rods 3 are pivotally connected with a post 7 which arises from the wheeled body 8 of the machine, the inner ends of rods 4 being pivotally connected with corresponding corners of said body. The inner ends of rods 5 are pivotally connected with a longitudinally extending rod 9 and the inner ends of rods 6 are pivotally connected with the respective ends of said rod 9. Also pivotally connected with the rod 9 medially of the ends thereof is an arm 10 carrying at its rearward end a rudder 11 of conventional design. Stay wires 12 co-operate with the arm 10 to hold the latter against lateral movement or swinging, permitting, however, of free vertical swinging of said arm. The point of pivotal connection between the arm 10 and rod 9 is spaced slightly from the forward end of arm 10. Co-operating with said arm are flexible elements 13 and 14 the upper ends of which are connected with said arm at opposite sides of the pivotal point thereof, the lower ends of said flexible elements being wrapped upon rotatable drums 15 suitably mounted in the bottom of body 8.

With the construction set forth it will be seen, that the elements 13 and 14 serve the double function of normally holding the arm 10 in horizontal or flying position and of rocking the inner ends of the sets of rods co-operating with the frame A toward each other, it being clear that, upon tightening of the elements 13 and 14, the rod 9 will

be drawn downwardly and the body 8 will be drawn upwardly. When this is done the inner ends of rods 5 and 6 will necessarily be rocked downwardly and the inner ends of rods 3 and 4 rocked upwardly, with the result of distending the frame A and consequently drawing taut the central plane portion B. In this condition the machine is, of course, adapted for flying. In case of accident and enforced sudden descent, it is only necessary to release the flexible elements 13 and 14. When this is done, the controlling rods of frame A will be released so as to permit of said frame diminishing in size, the arm 10 being simultaneously released so as to permit of the latter automatically swinging upwardly in order to serve as a sort of balance in the descent of the machine. Upon the release of the rods 3, 4, 5 and 6, as mentioned, the resistance of the air upon the under side of plane portion B will cause the latter to be flexed upwardly into parachute form, with the result of breaking the fall of the machine so as to carry the operator or aviator to safety without disastrous results which might otherwise have occurred.

While I have illustrated and described the preferred form of construction for carrying my invention into effect, this is capable of variations and modifications without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. In an aeroplane, the combination of a plane comprising a frame variable in size, and a flexible central portion, the periphery of which is secured to said frame; and two sets of substantially radially disposed rods having their outer ends pivotally connected with said frame, adapted to hold the latter in distended condition so as to retain said central portion drawn taut, the inner ends of the rods of each of said sets being pivotally connected together, and said sets of rods being adapted to rock in opposite directions from the plane of said frame to cause contraction of the size of the latter and permit of the central portion of the plane assuming parachute form, substantially as described.

2. In an aeroplane, the combination of a plane comprising a frame variable in size, and a flexible central portion having its periphery secured to said frame; and means for releasably holding said frame in distended condition so as to retain said central portion drawn taut, said means being adapted to move in opposite directions from

the plane of said frame to cause contraction of the size of the latter and permit of the central portion of the plane assuming parachute form, substantially as described.

3. In an aeroplane, the combination of a plane comprising a frame adjustable in size, and a flexible central portion having its periphery secured to said frame; two sets of rods having their outer ends pivotally connected with said frame, the inner extremities of the rods of each of said sets being pivotally connected, said sets of rods projecting angularly in opposite directions from the plane of said frame to contract the latter and permit of said central portion of said plane assuming parachute form; and means for rocking said inner ends of said sets of rods toward each other to distend said frame and cause the central portion of said plane to be drawn taut, substantially as described.

4. In an aeroplane, the combination of a normally substantially flat plane; means for distorting said plane into parachute form; and a pivotally mounted rudder-carrying arm adapted to assume a perpendicular position when said plane is in parachute form, substantially as described.

5. In an aeroplane, the combination of a plane comprising a frame adjustable in size, and a flexible central portion having its periphery secured to said frame; two sets of rods having their outer ends pivotally connected with said frame, the inner extremities of the rods of each of said sets being pivotally connected, said sets of rods projecting angularly in opposite directions from the plane of said frame to contract the latter and permit of said central portion of said plane assuming parachute form; means for rocking said inner ends of said sets of rods toward each other to distend said frame and cause the central portion of said plane to be drawn taut; and a pivotally mounted rudder-carrying arm connected with said frame adapted to assume a perpendicular position when said plane is in parachute form, substantially as described.

6. In an aeroplane, the combination of a plane comprising a frame adjustable in size, and a flexible central portion having its periphery secured to said frame; two sets of rods having their outer ends pivotally connected with said frame, the inner extremities of the rods of each of said sets being pivotally connected, said sets of rods projecting angularly in opposite directions from the plane of said frame to contract the latter and permit of said central portion of said plane assuming parachute form; means for rocking said inner ends of said sets of rods toward each other to distend said frame and cause the central portion of said plane to be drawn taut; a pivotally mounted rudder-carrying arm connected with said frame

adapted to assume a perpendicular position when said plane is in parachute form; and means for releasably holding said rudder-carrying arm substantially coplanar with
5 said frame and said sets of rods in a position in which the same distend said frame, substantially as described.

In testimony whereof I have signed my name to this specification in the presence of two subscribing witnesses.

CARL JOHNSON.
